UNITED STATES PATENT OFFICE.

CHARLES B. FITHIAN, OF PHILADELPHIA, PENNSYLVANIA, ASSIGNOR OF ONE-THIRD
TO ALBERT GENTEL, OF PHILADELPHIA, PENNSYLVANIA, AND ONE-THIRD TO IRA
L. STANGER, OF PENSAUKEN, NEW JERSEY.

ADAPTER FOR CUT-OUT BLOCKS.

1,181,298.

Specification of Letters Patent.

Patented May 2, 1916.

Application filed February 20, 1915. Serial No. 9,535.

To all whom it may concern:

Be it known that I, CHARLES B. FITHIAN, a citizen of the United States, residing at Philadelphia, in the county of Philadelphia and State of Pennsylvania, have invented 55 certain new and useful Improvements in Adapters for Cut-Out Blocks, of which the following is a specification.

My invention relates to an adapter for 10 cut out blocks, that is to say, to a device adapted to be used in an electrical cut out block designed for use with cartridge type fuses whereby a plug type fuse may be utilized in such cut out block.

15 Heretofore cut out blocks have been made in two main distinct types, one adapted for use with fuses of the type known to those skilled in the art as cartridge fuses, and the other adapted for use with fuses of the type 20 known as plug fuses. The cartridge type fuses are generally more expensive, and for other reasons it is sometimes desirable to use a plug type fuse in a cartridge type fuse block.

25 The object therefore of my invention is to provide a simple and efficient device for insertion in a cut out block designed for cartridge type fuses whereby fuses of the plug type may be utilized in such a cut out block.

30 The nature and characteristic features of my invention will be more readily understood from the following description taken in connection with the accompanying drawings forming part hereof, in which—

35 Figure 1 is a top or plan view of a common form of cut out block designed for use with cartridge type fuses but with the device of my invention shown mounted therein; Fig. 2 is a longitudinal section thereof taken 40 on the line 2—2 of Fig. 1; Fig. 3 is an end elevation thereof; Fig. 4 is a perspective view of the adapter detached; and Fig. 5 is an underneath plan view of the same.

45 Referring to the drawings, the cut out block there shown is of a common and well known type and comprises a suitably molded porcelain base 6 upon which the various parts are mounted, being provided with the usual metal connection terminal plates 7. 50 Mounted in the base 6 and electrically connected with the terminal members 7 are

spring clips 8 which project upwardly from the block 6 and are adapted to receive and retain cartridge fuses, which, as well known to those skilled in the art, comprise cylindrically shaped devices having external metal terminals adapted to be engaged in said spring clips 8 to thereby establish the electrical connection at each end thereof, and having the internally arranged fuse wire 60 which is adapted to be "blown" when an excess of current passes through the circuit. As these fuses are widely known and used, further description thereof is unnecessary.

65 As before stated the purpose of the device of my invention is to permit the use of plug fuses in cut out blocks adapted for use with cartridge type fuses. It is also well known that the plug type fuse comprises a device 70 principally formed of insulating material such as porcelain providing an interior chamber for the fuse wire, and having an external metallic portion, usually threaded, for establishing the electrical connection with one end of said fuse wire, and also a 75 centrally arranged button in one end of the plug forming the electrical connection for the other end of the fuse wire. Such a device is shown in Figs. 1, 2 and 3 of the drawings in operative relation in the adapter, the 80 external screw threaded metallic portion being numbered 9 and the centrally arranged button being numbered 10. Further description of the fuse plug is also unnecessary as 85 these devices are well known in the art, being widely used and also varying somewhat in minor details of construction.

90 The device comprising the novel portion of my invention consists of a receptacle having an internal metallic portion 11 adapted to receive the fuse plug, being complementary to the conformation thereof and having a block 12 of porcelain or other suitable insulating material mounted in the base thereof. A screw 13 is centrally mounted in the insulating block 12 and is provided with a head 14 which is adapted to form a contact for the button 10 provided on the end of the fuse plug. Secured to the screw 13 both mechanically and electrically by means of a 95 nut 15 is a metallic member 16 which extends from a terminal lug 17 which is pref-

erably cylindrical in conformation and of the same dimensions as the metallic end of the cartridge fuse which it is designed to supplant. The metal of the interior of the receptacle 11 is also continued downward as at 19 around the insulating block 12 and is preferably inturned at the bottom as at 20 to retain the insulating block 12 in place. On one side of the device in alinement with the terminal lug 17 there is also provided an oppositely disposed terminal lug 18 of conformation and dimensions similar to the terminal lug 17 but secured to and electrically connected with the lower continuation of the internal metallic portion 11. The terminal lugs 17 and 18 are preferably arranged with their common axis offset from the plane of the vertical axis of the receptacle 11 which receives the fuse plug, this arrangement being provided so as to effectually separate the fuse plugs of the adjacent lines as will clearly appear from an inspection of Figs. 1 and 3 of the drawings. The inner metallic portion 11 of the adapter and also the downwardly extending portion 19 thereof are surrounded by a cylindrical shell or cover 21 of suitable insulating material.

It will be seen that the current enters the fuse block from the line wire through one of the terminal connection pieces 7 and thence passes through the spring clip 8 to the terminal 18 of the adapter, thence passing to and through the internal metallic portion 11, thence through the fuse plug passing out through the button 10 to the head 14 of the screw 13, thence through said screw to and through the metallic member 16 to the terminal lug 17 of the adapter whence it passes to the other spring clip 8 and out through the corresponding terminal member 7 to the line wire.

It will, of course, be understood that the various parts will be made in conformity with the usual style and arrangement of electrical apparatus of this general description, the various metal parts being preferably made from stampings, in so far as possible, and it will also be understood that various minor changes may be made without departing from the spirit of my invention.

Having thus described the nature and characteristic features of my invention what I claim as new and desire to secure by Letters Patent is:—

1. An adapter for cut out blocks comprising a receptacle adapted to receive a fuse plug and having terminal lugs extending therefrom of cylindrical conformation and adapted to be mounted in a cut out block designed for cartridge type fuses.

2. An adapter for cut out blocks comprising a receptacle adapted to receive a fuse plug, said receptacle having an internal metallic wall forming one of the electrical

connections for said fuse plug, a suitably insulated metallic member mounted in the base of said receptacle forming the other electrical connection for said fuse plug, and a pair of terminal lugs extending from said receptacle, said terminal lugs adapted to be mounted in a fuse block designed for cartridge type fuses and being electrically connected one to each of the interior metallic portions of said receptacle.

3. An adapter for cut out blocks comprising a receptacle adapted to receive a fuse plug, said receptacle having an internal metallic wall forming one of the electrical connections for said fuse plug, a suitably insulated metallic member mounted in the base of said receptacle forming the other electrical connection for said fuse plug, and a pair of terminal lugs extending from said receptacle, said terminal lugs adapted to be mounted in a fuse block designed for cartridge type fuses and being electrically connected one to each of the interior metallic portions of said receptacle, the axis of said terminal lugs being offset out of the plane of the axis of said receptacle.

4. An adapter for cut out blocks comprising a receptacle adapted to receive a fuse plug, said receptacle having an internal metallic wall, a block of insulating material mounted in the base of said receptacle, a centrally arranged metallic member mounted in said block and having an interiorly extending head, and a pair of terminal lugs extending from the sides of said receptacle, said terminal lugs adapted to be mounted in a fuse block designed for cartridge type fuses and being electrically connected one to each of the interior metallic portions of said receptacle.

5. An adapter for cut out blocks comprising a receptacle adapted to receive a fuse plug, said receptacle having an internal metallic wall, a block of insulating material mounted in the base of said receptacle, a centrally arranged metallic member mounted in said block and having an interiorly extending head, and a pair of terminal lugs extending from the sides of said receptacle, said terminal lugs adapted to be mounted in a fuse block designed for cartridge type fuses and being electrically connected one to each of the interior metallic portions of said receptacle, the axis of said terminal lugs being offset out of the plane of the axis of said receptacle.

6. An adapter for cut out blocks comprising a receptacle adapted to receive a fuse plug, said receptacle having an interior metallic wall and an exterior shell of insulating material, a block of insulating material mounted in the base of said receptacle, a centrally arranged metallic member mounted in said block and having an interiorly extending head, and a pair of termi-

nal lugs extending from the sides of said signed my name in the presence of two
receptacle, said terminal lugs adapted to be witnesses.
mounted in a fuse block designed for car-
tridge type fuses and being electrically con-
5 nected one to each of the interior metallic
portions of said receptacle.

In testimony whereof, I have hereunto

CHARLES B. FITHIAN.
